UNITED STATES PATENT OFFICE.

JOHN F. McGARRAHAN, OF CONGRESS PARK, ILLINOIS, ASSIGNOR TO J. S. GILES & SONS, OF CHICAGO, ILLINOIS, A CORPORATION OF ILLINOIS.

COMBINATION CAP NOZZLE WITH DETACHABLE CLOSING CAP FOR CANS.

1,411,573.

Specification of Letters Patent.

Patented Apr. 4, 1922.

Application filed January 13, 1921. Serial No. 436,935.

To all whom it may concern:

Be it known that I, JOHN F. McGARRAHAN, a citizen of the United States, residing at Congress Park, in the county of Cook,

5 State of Illinois, have invented certain new and useful Improvements in Combination Cap Nozzles with Detachable Closing Caps for Cans, of which the following is a description, reference being had to the accompanying drawing and to the figures of 10 reference marked thereon.

The invention relates to new and useful improvements in a combined cap nozzle with a detachable closing cap for cans, and more 15 particularly to a combined cap nozzle and closing cap which may be used not only as an original package but which may also be used for dispensing the contents of the package.

20 An object of the invention is to provide a can with a combined closing cap and a nozzle carrying cap which latter may be attached to the closing cap after it has been secured to the can.

25 A further object of the invention is to provide a combined closing cap and nozzle carrying cap wherein the closing cap is provided with a tapered sleeve adapted to receive the nozzle of the nozzle carrying cap 30 and frictionally grip the same so that the nozzle carrying cap may be attached to and shipped with the can which is closed by the closing cap.

A still further object of the invention is 35 to provide a construction of the above character wherein the sleeve on the securing cap serves also the function of holding the abutted edges of the nozzle in close contact so that it is not necessary to solder the side 40 seam of the nozzle.

Another object of the invention is to provide a cap of the above character wherein the nozzle is secured to its carrying cap by seaming instead of soldering.

45 In the drawings, which show by way of illustration one embodiment of the invention:

Figure 1 is a side view of a can having attached thereto my combined closing cap and nozzle carrying cap;

Fig. 2 is a sectional view on the line 2—2 of Fig. 1;

Fig. 3 is a vertical sectional view through the upper portion of the can with the nozzle carrying cap applied thereto and through

the securing cap which is attached to the nozzle;

Fig. 4 is a perspective view of the nozzle as detached from the carrying cap.

I have preferably shown my invention as 60 applied to a can which may be used for shipping and dispensing oil, and said can consists of a cylindrical body portion 1 having a closing end 2 which terminates in a threaded neck 3. The can is adapted to be 65 closed by a closing cap 4 which is formed with a thread in the usual manner and is adapted to engage the thread 3 on the can proper. This closing cap is adapted to be removed from the can and a nozzle carrying cap attached to the can. Said nozzle carrying cap is indicated at 5 in the drawings, and said cap is of similar construction to the cap 4, that is, it is provided with a thread adapted to engage the thread on the 75 can body proper.

The closing cap 4 is provided with a tapered sleeve 6. This tapered sleeve 6 is soldered to the closing cap proper, as indicated at 7—7 in Fig. 2. The nozzle carrying cap 5 is provided with a central opening through which is inserted a nozzle 8. This nozzle 8 is tapered so as to conform in shape to the tapered sleeve 6. Said nozzle is preferably formed by rolling the metal into the 85 proper tapered shape with the side edges 9 of the nozzle abutted. At the lower end the nozzle is provided with a flange 10 which is formed into a double seam with the flange 11 on the nozzle carrying cap. Thus the 90 nozzle is secured to the nozzle carrying cap by seaming, as distinguished from soldering, which makes a very quick way of securing the nozzle to the cap. The nozzle 8 is adapted to be inserted into the sleeve 6 and forced 95 in until the sleeve frictionally grips the nozzle. When in this position, the side edges 9 will be forcibly brought into abutting engagement and so no solder is necessary, for closing the side seam of the nozzle.

100 My improved combined closing cap and nozzle carrying cap is especially adapted for an oil can in which the oil is shipped as an original package, the can closed by the closing cap for shipment, and the nozzle is 105 attached and the can used as a squirt can for dispensing oil. It is essential that the closing cap will be firmly secured on the can in order to seal the same and prevent the leakage of the oil during shipment. The 110

closing cap is first placed on the can and the cap screwed down by the ordinary machine, which will screw the cap down with a uniform pressure and bring about a perfect closing which cannot be accomplished by hand means. After the cap has been secured on the can and the package closed, then the nozzle is inserted in the sleeve 6 and forced in until it tightly grips the same. This nozzle becomes a part of the package and may be shipped therewith as a unit. The nozzle extends to the right and left of the sleeve, as shown in Figs. 1 and 3, and also serves as a means for turning off the closing cap. When the nozzle is being used on the can, the closing cap remains on the nozzle and holds the side edges of the nozzle firmly in contact and when desired the nozzle carrying cap may be removed and the can temporarily closed by the closing cap. The closing cap is preferably provided with a sealing disk which is omitted from the drawings for the sake of clearness. It is obvious that minor changes in the details of construction may be made without departing from the spirit of the invention as set forth in the appended claims. Having thus described the invention, what is claimed is:—

1. The combination of a can, a closing cap therefor, a nozzle carrying cap, and means

on said closing cap detachably engaging said nozzle for permitting the assembly of said caps after said closing cap has been screwed onto the can. 35

2. The combination of a can, a closing cap therefor, a nozzle carrying cap, said closing cap having a tapered sleeve rigidly secured thereto and adapted to receive and grip the nozzle of the nozzle carrying cap. 40

3. The combination of a can, a closing cap therefor, a nozzle carrying cap having a nozzle attached thereto with the side edges of the metal forming the nozzle in abutted relation to each other, said closing cap having a tapered sleeve adapted to receive the nozzle and firmly grip the same and force said abutted edges of the nozzle into close contact with each other. 45

4. The combination of a can, a closing cap therefor, a nozzle carrying cap, means for detachably securing said nozzle to the closing cap, said nozzle carrying cap having the nozzle secured thereto by seaming. 50

5. The combination of a can, a closing cap and a cap having a nozzle, and means for detachably holding said caps in assembled relation by means of said nozzle. 55

In testimony whereof, I affix my signature.

JOHN F. McGARRAHAN.
